E. N. KERN,
LIQUID FUEL DISPENSING APPARATUS,
APPLICATION FILED NOV. 27, 1915.

1,210,812.

Patented Jan. 2, 1917.

Inventor
E. N. KERN

Attorney

Watson E. Coleman

UNITED STATES PATENT OFFICE.

EDWARD N. KERN, OF PORTSMOUTH, OHIO.

LIQUID-FUEL-DISPENSING APPARATUS.

1,210,812.

Specification of Letters Patent.

Patented Jan. 2, 1917.

Application filed November 27, 1915. Serial No. 63,877.

To all whom it may concern:

Be it known that I, EDWARD N. KERN, a citizen of the United States, residing at Portsmouth, in the county of Scioto and State of Ohio, have invented certain new and useful Improvements in Liquid-Fuel-Dispensing Apparatus, of which the following is a specification, reference being had to the accompanying drawings.

This invention relates to certain improvements in liquid fuel dispensing apparatus and is an improvement on the invention as embodied in my Patent No. 1,177,870, dated April 4, 1916, and it is an object of the invention to provide a dispensing apparatus of this general character having novel and improved means whereby the quantity of liquid to be dispensed may be determined with convenience and facility.

The invention consists in the details of construction and in the combination and arrangement of the several parts of my improved apparatus whereby certain important advantages are attained and the device is rendered simpler, less expensive and otherwise more convenient and advantageous for use, all as will be hereinafter more fully set forth.

The novel features of the invention will be carefully defined in the appended claims.

In order that my invention may be the better understood, I will now proceed to describe the same with reference to the accompanying drawings, wherein—

Figure 1 is a view in elevation with a portion broken away of a liquid dispensing apparatus constructed in accordance with an embodiment of my invention, and Fig. 2 is an enlarged fragmentary sectional view illustrating certain detail features of the section as herein embodied.

As disclosed in the accompanying drawings, 1 denotes a measuring tank in communication, through the medium of the pipe 2, with a suitable source of liquid supply 3, herein indicated as a tank, embedded within the ground and said pipe 2 discharges within the tank a predetermined distance above the base thereof although I do not wish to limit myself in the present embodiment of my invention to this exact arrangement. Interposed within the pipe 2 is a pump 4 preferably of a centrifugal type operated by a conventional electric motor M in electrical connection with a suitable source

of energy, said connection having interposed therein a cut-out switch S, for a purpose which is believed to be self-evident.

Extending through the base of the tank 1 and terminating at substantially the top 60 thereof is the return pipe 5, said pipe being also in communication with the supply tank 3. The portion of the pipe 5 within the tank 1 is provided with a plurality of predetermined vertically spaced openings 6, said 65 openings being arranged at various gallon levels within the tank 1. Coacting with each of the openings 6 is a valve 7 carried by the rock arm 8 and coacting with the rock arm 8 is the spring 9 which serves to maintain the 70 valve 7 normally in closed position. The upper end of the rock arm 8 is provided with an angular extremity 23 with which is operatively engaged a rod 10 extending 75 above the top of the tank and provided with a suitable operating means 11 whereby it will be perceived that the valve 7 may be opened when desired in order to assure the return of all liquid within the tank 1 in 80 excess of a predetermined quantity being returned to the supply tank. It is also of advantage to have the outer end portion of each of the rods 10 provided with a suitable identifying character.

12 denotes a vertically disposed gage glass 85 having its opposite extremities in communication with the interior of the tank 1 and of a height substantially equal to the height of the tank, said glass being arranged within a groove 14 formed in the side wall of the 90 tank 1. Arranged adjacent the groove 14 and disposed longitudinally thereof is a chart C provided with three longitudinally disposed rows of indications 15 and 16, the 95 row 15 being graduated to indicate the amount of liquid within the tank 1 while the indications 16 denote the value of the liquid in connection with the indications 15. Coacting with the chart C is the slide 17 provided with value indications 18 extending 100 downwardly on the slide. By the use of this slide it will be perceived that in the event all of the liquid retained in the tank 1 is not discharged the value of the liquid 105 discharged may be determined. For example, should five gallons be initially delivered within the tank 1 at a valuation of ten cents per gallon, and all of the liquid is not discharged or drained out, the slide 17 110 is drawn down to bring the top thereof to

the five gallon level, which shows fifty cents on the column or row 16 and if, for instance, fifteen cents of liquid remains in the tank 1, the indication 18 on the slide registering 5 with the liquid level on the column or row 15 will show thirty-five cents.

22 denotes a swinging door of suitable configuration hingedly engaged with the tank 1 and adapted to inclose the gage 10 glass 14 and the chart C so that the same may be effectively protected against the elements and abuse.

The parts of my present invention hereinbefore set forth constitutes, in the main, the 15 improvements embodied in the present application over my co-pending application hereinbefore referred to, and the parts illustrated in the accompanying drawings but not hereinbefore particularly referred 20 to or described are substantially identical to what is shown in my co-pending application, except that in the present instance I have deemed it advisable to provide the return pipe 5 at a predetermined distance be 25 low the base of the tank 1 with the upstanding elbow 19 to receive the discharge nozzle 20 so that the excess liquid within the measuring tank 1 may be discharged within the return pipe and for which reason the discharge nozzle 20 is flexibly connected with 30 the tank 1.

From the foregoing description, it is thought to be obvious that an apparatus constructed in accordance with my invention 35 is of an extremely simple and comparatively inexpensive nature and is particularly well adapted for use by reason of the convenience and facility with which it may be assembled, and it will also be obvious that 40 my invention is susceptible of some change and modification without material departure from the principles and spirit thereof and for this reason I do not wish to be understood as limiting myself to the precise arrangement and formation of the several 45 parts herein shown in carrying out my invention in practice.

I claim:

1. A device of the character described including a measuring tank in communication 50 with a suitable source of supply, a return pipe disposed vertically through the container, said return pipe being provided with a plurality of longitudinally spaced openings, a valve for controlling each of 55 said openings, means extending exteriorly of the tank for adjusting the valve into open adjustment, the exterior portion of said means being provided with an identity, a rock arm to which said valve is affixed 60 and with which the operating means coacts, and a spring coacting with the rock arm for maintaining the valve normally in a closed position.

2. A device of the character described including a measuring tank in communication with a suitable source of supply, a return pipe disposed vertically through the container, said return pipe being provided with a plurality of longitudinally spaced 70 openings, a valve for controlling each of said openings, means coacting with each of the valves and extending exteriorly of the tank for adjusting the valve into open adjustment, the exterior portion of said means 75 being provided with an identity, and means coacting with each of the valves for normally maintaining the same in a closed position.

3. A device of the character described including a measuring tank in communication 80 with a suitable source of supply, a return pipe in communication with the container, a discharge nozzle in communication with the container, and an elbow in communication 85 with the return pipe below the container and into which the nozzle is adapted to discharge.

In testimony whereof I hereunto affix my signature in the presence of two witnesses. 90

EDWARD N. KERN.

Witnesses:

WILLIAM E. KILCOYNE,
R. C. KILCOYNE.

DISCLAIMER.

1,210,812.—*Edward N. Kern, Portsmouth, Ohio. LIQUID-FUEL-DISPENSING APPARATUS.* Patent dated January 2, 1917. Disclaimer filed August 9, 1926, by the assignee, *Wayne Tank & Pump Co.*

Hereby disclaims from the scope of claim 3 of Patent 1,210,812, any liquid fuel dispensing apparatus in which the discharge nozzle does not enter an element which communicates with the return pipe when draining back liquid from the measuring tank to the source of supply.
